EUGENE SONNTAG, JR., OF ASTORIA, NEW YORK, ASSIGNOR TO M. BINKOVITZ & SON, OF NEW YORK, N. Y., A COPARTNERSHIP OF NEW YORK.

DESIGN FOR MATTRESS-TICKING.

59,293.

Specification for Design.

Patented Oct. 4, 1921.

Application filed June 15, 1921. Serial No. 477,830. Term of patent $3\frac{1}{2}$ years.

To all whom it may concern:

Be it known that I, EUGENE SONNTAG, Jr., a citizen of the United States, residing at Astoria, in the county of Queens and city and State of New York, have invented a new, original, and ornamental Design for Mattress-Ticking, of which the following is a specification, reference being had to the accompanying drawing, forming part thereof.

The said drawing illustrates the design, which is repeated indefinitely on the goods.

I claim:

The ornamental design for mattress ticking, as shown.
